[57] CLAIM

The ornamental design for a combination playhouse and picnic table, as shown and described.

DESCRIPTION

FIG. 1 is a top perspective view of a combination playhouse and picnic table, showing my new design; FIG. 2 is a front elevational view thereof.

FIG. 3 is a top plan view thereof.

FIG. 4 is a rear elevation thereof. The ladder has been omitted for clarity of illustration; and

FIG. 5 is a side elevational view thereof; the opposite side being a mirror image of FIG. 5.

Fig. 1.

Fig. 2.
